UNITED STATES PATENT OFFICE

BENJAMIN F. NELSON, OF LARCHMONT, NEW YORK, ASSIGNOR TO THE BEST FOODS, INC.,
OF NEW YORK, N. Y., A CORPORATION OF NEW JERSEY

DESIGN FOR A BOTTLE

Application filed December 5, 1931. Serial No. 41,972. Term of patent 14 years.

To all whom it may concern:

Be it known that I, BENJAMIN F. NELSON, a citizen of the United States, residing at Larchmont, in the county of Westchester and State of New York, have invented a new, original, and ornamental Design for a Bottle, of which the following is a specification, reference being had to the accompanying drawings forming a part hereof:

What I claim is:

The ornamental design for a bottle as shown and described.

BENJAMIN F. NELSON.
